UNITED STATES PATENT OFFICE

JOSEPH A. SCHERTZ, OF MARQUETTE, NEBRASKA.

HAY-STACKER.

No. 902,610.

Specification of Letters Patent.

Patented Nov. 3, 1908.

Application filed June 2, 1908. Serial No. 436,258.

To all whom it may concern:

Be it known that I, JOSEPH A. SCHERTZ, a citizen of the United States, residing at Marquette, in the county of Hamilton and State 5 of Nebraska, have invented certain new and useful Improvements in Hay-Stackers, of which the following is a specification.

This invention relates to an improved hay stacker, and has for one of its objects the 10 provision of means for elevating hay or other like produce to an unusually high altitude; another object is to provide means for use in forming more than one stack without changing the position of the stacker.

15 The invention includes certain devices found to be convenient for operating the parts, and includes features relating to durability and economy of construction, and to adjustable means for increasing the "sweep" 20 of the fork.

With these and other objects in view the invention presents a novel combination and arrangement of parts as described herein, pointed out by the claims and as illustrated 25 by the drawing, wherein,—

Figure 1 is a side view of a hay stacker embodying my invention, the fork being in a lowered position; a reinforcing-rail being shown broken away to disclose the pivotal 30 mounting of the frame. Fig. 2 is a somewhat similar view to that shown in Fig. 1, the fork being elevated; the base support being partly broken away. Fig. 3 is a rear view of parts shown in Fig. 1, the operating 35 crane or lever being sectioned at its pivotal mounting. Fig. 4 is an enlarged detail relating to Figs. 1, 2 and 3, to clearly show relative position of parts, the guide-rail being partly in section. Fig. 5 is a plan view of the 40 locking-bar and a part of the guide rail and swing-lever, said rail and lever being partly in section. Fig. 6 is a plan view of the fork, lifting arms and holding-plate, a part of the fork-controlling cable being also shown.

45 Fig. 7 is a view of the rear end of the fork.

Referring now to the drawing for a more particular description, numeral 1 indicates a hay stacker which may be provided with any suitable base 2 so that the revoluble and upright frame 3 may be sustained, substantially 50 in a vertical position.

Base 2 may be conveniently constructed by use of parallel bed-plates 4 upon which are secured side-plates 5, and between the 55 ends of side plates 5 are secured cross-plates 6. I employ a series of bearing-rollers or

wheels 7 pivotally mounted upon and sustained by straps 8, these straps being secured upon and extended above plates 5 and 6. The parts thus described provide a suitable 60 and inexpensive supporting base, preferably rectangular in form, since stacks are to be formed upon either side of it, as will be seen. Rollers 7 are preferably mounted oppositely disposed, as pairs so that the weight of the 65 upright, revoluble frame 3 may be adequately sustained.

I provide the disk 9 having its center pivotally mounted by pin 10 traversing the middle of the disk and base block 11, said 70 base block being secured between side plates 5. The upright frame 3 consists of four corner posts 12, one of which, however, for convenience is indicated at 12'; an upper structure is added to these posts, as will be 75 described. These corner posts have their lower ends secured upon and near the outer edge of disk 9 at equal distances apart, and reinforcing rails 79 may be employed, as clearly shown, for securing the posts. Said 80 posts extend upward convergently, and at their upper ends and upon their outer sides I preferably employ inverted U-shaped plates 13, which operate as reliable securing 85 means; the posts are also held in fixed relation to each other by the horizontal U-shaped holding-plate 14, having parallel arms 15 secured upon plates 13. I do not wish to be understood as limiting myself to the exact 90 details mentioned, and other means may be employed, if desired, for securing the corner posts. In elevating large loads of hay there is a considerable strain upon the frame, and all of the parts should be adequately sustained. 95

Lifting-arms 17 are sustained upon arms 15, their pivotal mounting being shown at 16. Arms 15 are apertured near their ends as shown at 18, to furnish a pivotal mounting for arms 17 when it is desired to elevate 100 fork 19 to an altitude greater than it would be elevated when mounted as at 16.

Frame 3 is extended upward to its apex 20 from the upper ends of posts 12 preferably as an iron structure, employing legs 21 suitably secured upon said posts. The material used or particular form of this upper structure is not important, however, so long as a suitable mounting is provided for operating-lever 22, and for pulley 23. The operating-lever or crane 22 is pivotally mounted 105 at 24 upon plates 25, these plates being 110

secured upon legs 21. Between plates 25 and apex 20 are secured plates 26 upon which pulley 23 is mounted. As thus described, operating lever 22 is mounted to swing in the same direction as arms 17. Longitudinally disposed upon each arm 17 is secured rod 27 upon which is a ring 28, and I employ a pair of connecting cables 29, one end of each cable being secured at 82 to the front end of operating lever 22, the opposite ends of these cables being connected to rings 28. Upon the rear end of lever 22, at 83, is secured cable 30, which passes over pulley 31, secured upon the rear of base 2, and any suitable power may be employed for drawing the cable; and as is apparent, a movement of this cable when drawn outward, will operate lever 22 to raise lifting-arms 17.

20 Fork 19, best shown in Fig. 6, comprises tines 32 secured by cross-piece 33, and, in order that provision may be made for a suitable mounting of the fork upon arms 17, the tines are assembled in groups, as the central group 34 and side groups or pairs 35. I employ inclined braces 36 extending upwardly from the rear end of pairs or groups 35 to posts 37, the latter being secured transversely upon the rear end of tine-group 34, and by this construction an open space or recess 38 is provided, within which extensions 39 of lifting-arms 17 may pass to pivotal mountings 40 upon cross-piece 33, and upon the lower part of the fork. Posts 37 are supported by braces 41, and upon the upper end of these posts are secured longitudinal rods 42, having thereon, rings 43.

40 Arms 17 are secured together by cross pieces 44 and 45, and by diagonal braces 46, and upon the middle of cross piece 44 is secured pulley 47. I employ cable 48, having end-ports 49 secured to rings 43; cable 48 engages pulley 47 and passes over pulley 23 upon frame 3, and thence passes downward to sustaining-bar or latch 50 upon which it is secured, as shown at 51. As thus described, the fork may have a swinging movement under control of cable 48. As shown in Figs. 1 and 2, posts 37 are substantially vertical, and tines 32 are horizontal. These posts remain vertical while the fork is being elevated. After a load has been placed upon the fork, the rear end of operating-lever 22 may be lowered by the power employed; this movement will raise arms 17 and the load will thereby be elevated, bar 50 remaining stationary at this time and sustaining fork 19, so that posts 37 remain in a vertical position while the load 60 is moving upward; and posts 37 remain vertical, under control of latch 50, until the fork is "dumped", and this operation will presently be explained.

Secured upon and near the rear ends of side, base-plates 5 are posts 52, upon the top

of which is secured engaging-rail 53, having notches 54, within which may be held the rear end of swing-lever 55, the latter having a pivotal mounting at 56 upon one of front posts 12.

70 Between rear posts 12 and 12' is mounted the reel or drum 57 upon one end of which is mounted the ratchet-wheel 58 engaged by the pawl 59. Upon lever 22, between its rear terminal and its pivotal mounting 24 is secured, at 60, the end of cable 61, the opposite end of this cable being secured in groove 62 of the reel. In groove 63 of the reel is secured cable 64, and to cable 64 is secured the weight 65.

75 Upon the rear post 12' is secured the guide-rail 66 which extends, substantially, parallel with and inwardly of post 12'. This guide rail is extended downward, and near its lower end is formed to provide the recess 67 and shelf 68.

80 Upon the lower part of corner post 12' and upon its outer side, I construct the guide-rail 69, the same being disposed longitudinally thereon and having an aperture 70 near its upper end adapted to receive therein, trip-rod 71, said rod having one end pivotally mounted at 72 upon the outer end of pawl 59, its opposite terminal being disposed adjacent lever 55, and, upon occasion 95 adapted to make contact with said lever, for purposes hereafter explained.

I provide the locking-bar or keeper 73, pivotally mounted at 74 upon swing-lever 55. Between keeper 73 and lever 55 is provided 100 the spring 75. Guide-rail 69 is apertured at 76, and the inner end of keeper 73 is transversely bent to form the finger 77. By reason of the resiliency of spring 75, finger 77 normally presses inwardly to engage within 105 aperture 76, and as shown by Fig. 5, may enter recess 81 to thereby detain lever 55 in a fixed relation within one of recesses 54 of rail 53.

I provide the detaching-bar 78 mounted 110 upon the outer part of the guide rail 66. The latch or sustaining-bar 50 has its pivotal mounting at 80 upon a front corner post 12; it passes within guide-rail 66 and its free end passes rearwardly of recess 67, and this latch 115 is adapted to have a seating, near its end, within said recess, in contact with and beneath shelf 68. By manually swinging said bar 78 in an inward direction, latch 50 will be dislodged from shelf 68, thereby allowing 120 the latch to swing upward, and it is obvious that this operation will permit tines 32 of the fork to move to a vertical position, and this constitutes the means for "dumping" or unloading the fork.

125 From the description thus given it will be understood, that when the rear end of operating lever 22 swings downward, it is detained by pawl 59, since weight 65 causes reel 57 to revolve, and cable or strand 61 be-

comes wound upon the reel. Ratchet 58, upon the end of the reel, is engaged by the pawl, and after the rear end of operating-lever 22 has been lowered to the position shown in Fig. 2, it is securely held by the pawl. At this time, the fork is in an elevated position, and its tines are horizontal for sustaining thereon the load which theretofore was placed thereon. During the 10 movement just described, cable 30 is drawn outward to pass upon pulley 31, and this movement is aided, somewhat, by weight 65.

As soon as the fork has been elevated, the operator manually presses the outer end of lever 73, sidewise, in a direction of lever 55, thereby raising finger 77 from aperture 76. Lever 55 is then raised upward sufficiently to lift it from recess 54 of rail 53. Frame 3 may then be readily rotated 90 degrees, in 20 either direction, by the operator, by pushing or pulling lever 55, sidewise, whereby fork 19 is moved sidewise to the location of the stack. After the fork has been thus moved to the desired position, it is dumped, by 25 manually moving the detaching-bar 78, as already described. The operator then swings frame 3, to carry fork 19 away from the stack, and by then raising lever 55 somewhat further, it will make contact with the 30 lower end of rod 71, which will raise this rod, thereby carrying pawl 59 out of engagement with the teeth of ratchet wheel 58, which releases operating-lever 22.

As soon as lever 22 has been released, its 35 front end will move downward, arms 17 and fork 19 having similar movements. The parts are so balanced that the fork and arms 17 have a weight somewhat greater than weight 65 plus the weight or friction 40 of other parts to be overcome, and, in operation arms 17 swing downward with a gradual movement, as soon as the reel has been released from the pawl, and this, as has been seen, is under control of the operator, who, 45 at the proper moment, raises lever 55 to push upward the trip-rod 71. By repeating the operations, as described, successive loads may be carried from the ground to the stacks, and these stacks may be formed upon either or 50 both sides of the stacker.

I have shown a plurality of recesses 54 formed in rail 53, and in operation, swing-lever may be inserted in any of these recesses, as desired.

55 During the revoluble movements of frame 3, the weight of the several parts is sustained upon rollers 7; these rollers have a broad surface for contact with the lower surface of disk 9.

60 Operating-lever 22 may have a greater length than shown, if desired, and by reason of the power derived from this lever and by use of weight 65, very large loads may be moved by the fork.

65 Rods 27 are constructed so that when arms

17 are mounted in apertures 18 of plate 15, said rods will have an adequate length to sustain rings 28 together with strands or cables 29, for the front end of the operating-lever.

70

Having given a full description, what I claim as my invention and desire to secure by Letters Patent, is,—

1. In a hay stacker, the combination of a supporting-base, a revoluble frame mounted 75 upon the supporting-base, a loading-fork; a pair of lifting-arms having their rear terminals pivotally mounted upon the revoluble frame, their front terminals pivotally mounted upon the loading-fork; an operating-lever pivotally mounted between its ends 80 upon the revoluble frame and having a connecting member between one of its ends and the lifting-arms; means to swing the opposite end of the operating-lever in a downward direction for raising the lifting-arms; means for detaining the lifting-arms when in an elevated position; means upon the revoluble frame for controlling the movements 85 of the loading-fork upon its pivotal mounting, and means to release the lifting-arms while they are in an elevated position.

2. In a hay stacker, the combination of a supporting-base, a revoluble frame mounted upon the supporting-base, a loading-fork; a 95 pair of lifting-arms provided with longitudinal rods; said lifting-arms having their rear ends pivotally mounted upon the revoluble frame, their front ends pivotally mounted upon the loading-fork; means upon 100 the revoluble frame to adjust the pivotal mounting of the rear ends of the lifting-arms; an operating-lever pivotally mounted between its ends upon the revoluble frame; supporting-members having one of their 105 ends slidably mounted upon the longitudinal rods of the lifting-arms, their opposite ends mounted upon one end of the operating-lever; means to swing the opposite end of the operating-lever in a downward direction for raising the lifting-arms; means for 110 detaining the lifting-arms when in an elevated position; means upon the revoluble frame for controlling the movements of the loading-fork upon its pivotal mounting, and 115 means to release the lifting-arms while they are in an elevated position.

3. In a hay stacker, the combination of a supporting-base, a revoluble frame mounted upon the supporting-base, a loading-fork; a 120 pair of lifting-arms having their rear terminals pivotally mounted upon the revoluble frame, their front terminals pivotally mounted upon the loading-fork; an operating-lever pivotally mounted between its ends 125 upon the revoluble frame and having a connecting member between one of its ends and the lifting-arms; means to swing the opposite end of the operating lever in a downward direction for raising the lifting-arms; 130

means upon the revoluble frame for controlling the pivotal movements of the loading-fork; means to release the lifting-arms while they are in an elevated position; a gravity-actuated reel having a ratchet-wheel thereon; a pawl normally engaging the ratchet-wheel; a strand upon the operating-lever and connected with the reel, and means

for controlling engagement of the pawl with the ratchet-wheel.

In testimony whereof I have affixed my signature in presence of two witnesses.

JOSEPH A. SCHERTZ.
